METHOD OF AND MEANS FOR PROPELLING AND CONTROLLING VESSELS

Filed Feb. 27, 1920

INVENTOR:
Thomas G. Tullock,
By *Mississippiana*
Atty.

UNITED STATES PATENT OFFICE.

THOMAS G. TULLOCH, OF LONDON, ENGLAND.

METHOD OF AND MEANS FOR PROPELLING AND CONTROLLING VESSELS.

Application filed February 27, 1920. Serial No. 361,707.

To all whom it may concern:

Be it known that I, THOMAS GREGORIE TULLOCH, major late Royal Artillery, a subject of the King of Great Britain, and a resident of Bank Buildings, King Street, St. James's Street, London, S. W. 1, England, have invented an Improved Method of and Means for Propelling and Controlling Vessels, of which the following is the specification.

This invention relates to the propulsion and control of vessels, rafts, and the like, by the combustion or explosion of gaseous fuels acting on the water through the medium of a reciprocating plunger or piston, or of two pistons suitably connected together.

In the preferred construction or arrangement I provide two cylinders in alignment having pistons suitably connected together preferably by a rod.

The axes of the two cylinders are inclined preferably at the smallest possible angle to the longitudinal axis and horizontal plane of the vessel to be propelled, the piston of the upper cylinder being adapted to operate by internal combustion, and the piston of the lower to act directly upon the water in which the vessel floats. An opening or aperture is formed in the bottom or side of the vessel, preferably the former, having its axis continuous with that of the lower cylinder, and it is thus adapted to direct the stream of water rearwardly, which stream is moved directly by the piston located at the upper end of the aperture.

The internal combustion cylinder may operate upon the four stroke, two stroke or other known cycle, and the lower end of the closed cylinder may be employed to deliver air or charge to the upper end of the cylinder in the usual and known manner in internal combustion engines. Suitable means are employed if the four stroke cycle is used to move the pistons during the three non-power strokes, and if a two stroke cycle is used, during the return stroke.

Means may be provided to ensure that while the pistons may make their outstroke rapidly, the return stroke shall be made relatively slowly, and this means may comprise a cam or cam grooved plate mounted upon a controlled rotating shaft, the cam or cam groove being so formed of oval shape with one flattened side that the operative face or groove is comparatively straight on

the one side, which side corresponds to the outward rapid movement of the pistons, the curved side being the longer track the pistons perform the return stroke slowly.

A suitable number of such cylinders or pairs of cylinders each provided with said discharge apertures for water may be arranged transversely across the vessel.

Arrangements may be made to operate all the combustion engine cylinders at once or separately or in groups for example those on one side of the vessel only, as may be desired.

I provide a blade or plate pivotally or hingedly mounted on the under surface of the ship or vessel. The hinged plate or blade is arranged opposite to and at the rear of each discharge aperture for the delivery of water.

The shaft or pivot upon which the blade or plate is mounted has operating and controlling means on the inside of the ship, so that the blades or plates may be inclined forwardly at a suitable angle facing the discharge of water from the apertures on the under surface of the vessel. By this means the water may be deflected and driven forwardly instead of rearwardly so that the operation of the moving stream of water is reversed and the vessel will therefore move in the opposite direction, that is to say, be driven astern. Such plates may take the place of rudders by being moved to a suitable angle upon their pivot shafts, for example, a right angle with the surface of the water. The said plates may be arranged to be operated singly or in one or more groups on either side of the keel of the boat, thus forming rudders to turn or manœuvre the vessel. The controlling motion from the interior of the ship is adapted to move the plates to any desired angle with relation to the under surface of the vessel, or to place the plates flat against the bottom of the vessel when desired to ensure that they shall not produce resistance to forward movement.

An auxiliary water intake arranged in advance of or forwardly of the said delivery aperture for water may be provided in order to assist in filling the lower cylinder with water on the return stroke of the piston.

It is necessary that the outward stroke or movement of the piston or pistons must be

made as quickly as possible so that the water shall be impelled or delivered through the delivery aperture as rapidly as possible.

The water displacing members instead of being circular may be of any suitable section.

Means may be provided such as a sliding valve to cut off the lower cylinder from the water delivery aperture to permit of adjustment or repair.

And in order that my invention may be completely understood, reference should be made to the accompanying sheet of drawings in which my invention is shown diagrammatically and by way of example to illustrate one mode of carrying it into effect.

Fig. 1 is a plan showing a pair of internal combustion engines which are coupled directly to pistons operating as water impellers. Fig. 1 also shows in plan a pair of the blades or plates before referred to pivotally or hingedly mounted on the under surface of the ship or vessel.

Fig. 2 is an elevation, part section of the cylinders as in Fig. 1, and with the plate or blade shown in full lines and in the reversing position, the dotted lines indicating other angular positions for operation.

AA are the internal combustion engine cylinders mounted on a suitable frame or bedplate A¹ which is secured upon or adjacent to the bottom of the ship or vessel. Each of the working pistons B which are adapted to reciprocate in the said two cylinders AA is connected by a piston rod C rigidly to a second piston D (see the section Fig. 2) which piston D is adapted to reciprocate in the cylinder E. The cylinders E are secured upon the same frame or bedplate A¹ as that upon which the internal combustion engine cylinders AA are mounted and in such a manner that the cylinders A and E have their axes in alignment. The cylinder E has an extension thereof E¹ also in axial alignment. This aligned axis of the two cylinders and the extension E¹ is at an acute angle as shown in Fig. 2, with the lower surface G of the ship or vessel or the like, the end of the cylinder E¹ being truncated to meet the angle of the under surface G of the ship or vessel.

The lower end of the cylinder E¹ is open to the water in which the ship or vessel floats by the delivery opening E².

Any suitable means may be provided to control the reciprocation of the piston B and D, but the means preferred comprise a transverse shaft F mounted in suitable bearings preferably just above the piston rods C C; the shaft F may be rotated in any suitable manner by other power such as an internal combustion engine shown at X, and at the desired controlled speed. A cam F¹ is rigidly secured upon the shaft F between bearings and adjacent the reciprocating

piston rod C. Pins C¹ C² are rigidly secured upon the piston rod C and means are provided to prevent the piston rod C and the pistons B and D secured thereto from turning. The shaft F being rotated by independent power, and in the direction indicated by the arrow, the cam F¹ in engaging the pin C², during its rotation, moves the rod C by means of the pin C², and therefore, the piston B to make a compression stroke,

the compression stroke being made, and the ignition being then effected by the spark plug diagrammatically shown in Figure 2, the explosion operates freely upon the two pistons C and D. In making the outward stroke, the pin C² during this stroke moves against the flat face which is nearly radial of the cam F¹. The continued rotation of the cam insures in the event of failure to ignite in the cylinder A, the inward stroke of the piston rod by engaging the other pin C¹. This movement it will be observed of the two pistons is effected relatively slowly by the scroll cam face. At maximum compression the charge in the cylinder A is fired. On the explosion of the charge the form of each cam F¹ permits the pistons B and D under the effect of the explosion to

make a rapid unimpeded outstroke, so permitting the whole force of the explosion to quickly operate upon the body of water contained in the cylinders E and E¹, which water is driven rearwardly by the piston D through the outlet orifice E² to impel the vessel forwardly.

It will be understood that the working cylinders A shown diagrammatically may operate upon either the two or the four stroke cycle.

Two such combined internal combustion engine cylinders such as A with water impelling cylinders such as E may be provided in one vessel as shown in Fig. 1. They may be conveniently arranged parallel with and equidistant from the centre line fore and aft of the ship or vessel G, the bottom surface of which is indicated in Fig. 2. The combined water impelling unit may however be placed in any convenient position for propulsion of the vessel, and although shown as arranged fitted on the bottom of the vessel, they may be placed at the side if desired. Further, although only two such unit combinations of power and impelling cylinders are shown in the plan, Fig. 1, a multiplicity of such combined units to any desired and convenient number may be arranged on the bottom of the vessel or some may be arranged on the bottom of the ship or vessel and others at the side. Moreover, steering may be effected by stopping the operation of the combined impelling unit or units on one side of the central vertical plane of the vessel, and continuing to operate one or some or all of these upon the other side of

the vessel, I may also arrange a plurality of such water impelling units if desired in order to drive the ship or vessel astern, I prefer however for this purpose, i. e., that of driving the ship or vessel astern, to effect this by means of the plate or blade H. This is shown in full lines in Fig. 2 in the vertical position, but it may be made to assume any other position as occasion demands.

- 10 The plates or blades H are arranged in such a manner that they may be moved to project from the bottom of the ship or vessel at the rear of and adjacent the water impelling outlets or tube extensions E². The 15 blades H are mounted upon a transversely arranged shaft J so arranged preferably in a recess formed on the under surface of the vessel that each blade or plate H when in the inoperative position may be turned upon the shaft J to practically fill the said recess in such a manner that the plate or blade is then flush with the under surface of the vessel. The shaft J which is mounted in suitable bearings extends transversely across 20 the said recess (not shown) and passes at each end of the lateral recess through a gland or stuffing box indicated at J¹, and an additional bearing indicated by the letter K may be provided in the centre of the said 25 recess. The two ends of the said shaft J which project within the vessel from the said glands are provided with means for rocking or oscillating the shaft. These means are indicated by the shaft L upon which is 30 mounted the worm M gearing with the quadrant N, which quadrants are rigidly secured upon the shaft J, preferably one at each end thereof. When the shaft L is turned in one direction the shaft J operated by the worm 35 M and the quadrant N causes the blades H or one of them secured to the shaft J to turn to the vertical position or at an angle normal to the stream of water shown in Fig. 2, in which position the water impelled through 40 the outlet E² by the piston D impinges upon the blade and thus causes the rearwardly directed stream of water meeting the said blade to be redirected forwardly instead of rearwardly, so reversing the vessel. As 45 shown by the dotted lines H¹, Fig. 2, the angle of position of the blade for receiving the stream of water may be varied as may be desired, or as before stated one plate or blade only may be operated separately, while the 50 other is retained flat against the bottom or side of the ship, the plate thus operated when projecting constituting a rudder to turn or manoeuvre the vessel.

55 The channel O is provided forward of the outlet E² in order to assist in filling the cylinder E¹ with water on the return stroke of the piston.

60 The sliding or gate valve P is fitted between the cylinder E and the cylinder or extension E¹ in order to completely close the

cylinder E and exclude water from same when it is desired to make an adjustment or effect repairs to the apparatus described. It will be understood that the valve P is completely open when the pistons B and D 70 are working.

Means are provided such as a wheel P¹ for operating the screw down gate valve P.

A plurality of the combined water impelling units as described may be placed on 75 each side of the centre line fore and aft of the ship, or of the keel, and those on one side of the vessel may be operated, while those on the other side are stationary, in order to manoeuvre the vessel, or a greater 80 number of such plurality of power units may be operated on the one side than those on the other, either together with or in co-operation with or independently of the plates or blades H.

85 It will be observed that the apparatus described may be placed at the stern of a ship and in such position the stream of water may be directed parallel with the longitudinal axis of the vessel.

90 What I do claim as my invention and desire to secure by Letters Patent is:—

1. A propeller for vessels comprising a water cylinder communicating with an opening in the vessel, a piston operable in said water 95 cylinder, an explosive cylinder, a piston operable in said explosive cylinder, means connecting the two pistons, and means for operating the explosive cylinder piston for compressing a charge in the cylinder, said operating means allowing a rapid movement of the piston in one direction but effecting a slow movement of the piston in the opposite direction.

100 2. A propeller for vessels comprising a water cylinder communicating with an opening in the vessel, a piston operable in said water cylinder, an explosive cylinder, a piston operable in said explosive cylinder, a rod connecting the two pistons, a shaft 110 mounted transversely of the piston rod, means for operating the shaft, and means carried by the shaft and engaging the piston rod for operating the piston to compress a charge in the explosive cylinder, said operating means allowing a rapid movement of the pistons on the explosion stroke but effecting a slow movement on the compression stroke.

115 3. A propeller for vessels comprising a water cylinder communicating with an opening in the vessel, a piston operable in said water cylinder, an explosive cylinder, a piston operable in said explosive cylinder, a rod connecting the two pistons, a shaft 125 mounted transversely of the piston rod, means for operating the shaft, and a cam secured on said shaft and adapted to engage the piston rod for operating the pistons to compress a charge in the explosive cylinder, 130

- 4
- said cam being so shaped as to allow a rapid movement of the pistons on the explosion stroke and effecting a slow movement on the compression stroke.
5. A propeller for vessels comprising a water cylinder communicating with an opening in the vessel, a piston operable in said water cylinder, an explosive cylinder, a piston operable in said explosive cylinder, a rod connecting the two pistons, a projection extending from said rod, a shaft mounted transversely of the piston rod, means for operating the shaft, and a cam secured on said shaft and adapted to engage the projection on the piston rod for operating the pistons to compress a charge in the explosive cylinder, said cam being so shaped as to allow a rapid movement of the pistons on the explosion stroke but effecting a slow movement on the compression stroke.
6. A propeller for vessels comprising a water cylinder communicating with an opening in the vessel, a piston operable in said water cylinder, an explosive cylinder, a piston operable in said explosive cylinder, means connecting the two pistons, means for operating the explosive cylinder piston for compressing a charge in the cylinder, said operating means allowing a rapid movement of the pistons upon the explosion of the charge, and a blade pivotally connected to the vessel and adapted to be swung either 50 into a position normal to the water stream or in a line with the water discharged from the water cylinder.
7. A propeller for vessels comprising a plurality of parallel water cylinders communicating with openings in the vessel, pistons operable in said water cylinders, a plurality of parallel explosive cylinders, pistons operable in said explosive cylinders, means for connecting aligned pistons, means for operating the explosive cylinder pistons for compressing charges in said cylinders, said operating means allowing a rapid movement of the pistons upon the explosion of the charge, blades adapted to be swung either into a position normal to the water stream or in line with the water discharged from the water cylinders, and means for rendering some of the aligned pistons inoperative.

T. G. TULLOCH.
